UNITED STATES PATENT OFFICE.

WILLIAM KOCHER AND WILLIAM J. RANCK, OF LOCKBOURNE, OHIO,
ASSIGNORS OF ONE-THIRD TO LEWIS R. YOUNG, OF SAME PLACE.

CORN-PLANTER.

SPECIFICATION forming part of Letters Patent No. 381,076, dated April 10, 1888.

Application filed December 23, 1887. Serial No. 258,833. (No model.)

To all whom it may concern:

Be it known that we, WILLIAM KOCHER and WILLIAM J. RANCK, citizens of the United States of America, residing at Lockbourne, in the county of Franklin and State of Ohio, have invented certain new and useful Improvements in Corn-Planters; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Our invention relates to certain new and useful improvements in corn-planters; and it consists in the novel construction and arrangement of the parts thereof, which will be more fully hereinafter described, and pointed out in the claims.

The object of our invention is to provide a corn-planter having peculiarly-arranged mechanism for operating the seed-slides unitedly, or through the medium of levers independently, the construction thereof being simple and effective, strong and durable, easily handled, and readily understood. We attain this object by the construction illustrated in the accompanying drawings, wherein like letters of reference indicate similar parts in the several views, and in which—

Figure 1 is a top plan view of our improved form of corn-planter. Fig. 2 is a sectional elevation thereof. Fig. 3 is a detail perspective view of one of the seed-boxes and its slide.

A indicates the frame, which has rearwardly-projecting strips A', which form bearings for the main shaft or axle B. The bearing-wheels B' are mounted upon this axle, and have suitable ratchet and pawl mechanisms connected thereto, for the purposes which will be readily understood in the art. Suitable arms, C, are hinged to the frame A, and project rearwardly, and are provided with seed-boxes C' at their rear ends.

The seed-boxes C' have enlargements c formed with one side thereof, in which the slide C² is mounted to open and close the seed-apertures in the bottom of the boxes, thereby regulating the flow through the depending seed-chutes C³,

secured to said boxes. Secured to each slide is a lever, C⁴, which projects ahead of the forward end of the enlargement c and engage with cam-wheels B², mounted upon the shaft or axle B in relative proximity to said levers. 55 By this means the slides are alternately opened and closed as the teeth upon the said wheels are arranged with cam-faces, and alternately arranged, as shown, so that one tooth will be adjacent to one face of the wheel and the next to upon the periphery thereof between two of the said teeth. The seed-boxes are also provided with boots D, which are connected by curved links to the arms C, which carry the seed boxes. The said boots have projections 65 d, in which blades d' are secured at an incline, and act to throw the ground over the seed after it is deposited. To the said projections d, in the rear of the boots D, one end of a lever, E, is secured, which projects to the forward 70 portion of the frame adjacent to the driver's seat. Each of the seed-boxes and boots are provided with this form of lever, and may be raised thereby, as desired, and when thus raised will be held by a suitable sector-rack, 75 d', as will be readily understood.

As shown in Fig. 2, a wheel, F, is mounted on the end of the shaft B, which is provided with diametrically-arranged rods or strikers f, which are adapted to strike against the inwardly-bent end of a marker-rod, G, that is pivotally secured to the side of the framework or to one of the arms C. This marker is bent in such a manner as to conform to the construction of the machine, and carries a narrow head or point, g, on its lower end. The inner end of the said rod bears against the coiled spring S, secured to the frame-work in any suitable manner, which has a tendency to normally keep the lower end of the marker 90 raised from the ground, as shown in Fig. 2. When, however, the wheel F revolves, the inner end of the marker-rod is pressed upward against the action of the spring S, so as to allow the striker f, secured to the wheel F, to 95 clear the said inner end of the marker-rod. While this operation is being accomplished the lower end of the marker is depressed into the ground. After the striker f passes the inner end of the marker-rod, the spring S im- 100

mediately throws the said inner end of the rod downward and the marking-point upward, and is thus held elevated until the next striker *f* engages with the inner end of the marking-
5 rod.

Centrally situated upon the shaft *B*, adjacent to the driver's seat, is a ratchet-and-pawl mechanism, which is adapted to regulate the action of the marker in turning. This is ac-
10 complished by grasping the said pawl *P* and operating it in connection with the ratchet-wheel, which revolves the shaft *B* and actuates the marker, as will be readily understood.

To limit the motion of the said pawl *P*, a rod,
15 *p*, is connected to the frame-work at its for-
ward end, and passing through the said pawl has an angular bend formed at its rear end, as
fully shown in Fig. 1, as at *p'*. By this means
the action of the said pawl *P* is made uniform,
20 and engagement thereof with the ratchet-
wheel is always attained.

It will be understood that slight changes in
the construction of the parts might be made
and substituted for those shown and described
25 without in the least departing from the spirit
and nature of our invention.

We claim—

1. The combination, with the frame having
a shaft or axle passing therethrough, of the
30 arms *C*, connected to the frame and extending
between and on the outside of the bearing-
wheels and carrying seed-boxes on their rear
ends, the enlargement or projections formed
35 on one side of each of the said seed-boxes, the
slides working in said enlargement, the lever-
arms connected to said slides and projecting
beyond the forward end of the said enlarge-
ment, and the toothed cam-wheels mounted
40 upon the axle and engaging with projecting
ends of the lever connected to the slides of
the seed-boxes, substantially as described.

2. The combination, with the main frame
having an axle arranged therein, as set forth,
toothed cam-wheels mounted on said axle, of the
45 arms *C*, hinged to the main frame and carrying
seed-boxes on their rear ends, projections
formed with one side of each seed-box, slides
working in said projections and seed-box and
having levers connected thereto which engage
50 with the toothed cam-wheels on the axle, the
boots or runners in connection with the seed-
boxes, and the rods and levers connected to
the rear portion of said boots or runners and
extending to the forward part of the machine
55 adjacent to the driver's seat, whereby said
arms, seed-boxes, and runners may be inde-

pendently raised from the ground, substan-
tially as described.

3. The combination, with the main frame, of
the arms *C*, hinged thereto, carrying seed-boxes 60
on their rear ends, the main shaft or axle car-
rying toothed cam-wheels, the slides for said
seed-boxes automatically operated by said
toothed cam-wheels, the boots or runners *D*, in
connection with the seed-boxes, the projec- 65
tions *d* on the rear side thereof, downwardly-
projecting arms or coverers *d'*, and the levers
E, all arranged as set forth, substantially as
described.

4. The combination, with the shaft or axle 70
mounted in the main frame, as set forth, of
the wheels *F* on each end thereof, having
strikers *f* diametrically arranged, the marker-
rod *G*, pivoted to the frame of the machine and
having an inner bent end adapted to engage 75
with the strikers *f* of the wheel *F* and the
coiled spring *S*, mounted in connection with
the frame of the machine and bearing upon
the upper part of the rod *G*, and acting to
normally keep the markers in a raised posi- 80
tion, substantially as described.

5. In combination with the main shaft or
axle, the ratchet-wheel mounted adjacent to
the driver's seat, the pawl *P*, adapted to en-
gage with said ratchet-wheel, the rod *p*, mounted 85
and constructed as set forth and passing
through the said pawl *P* to limit its movement
and cause a positive engagement of said pawl
with the ratchet-wheel, the wheels *F* on the
outer ends of the shaft, having strikers *f*, and 90
the spring-actuated marker *G*, substantially as
described.

6. In combination with the main frame, the
axle-shaft mounted therein, as set forth, hav-
ing the toothed cam-wheels, the hinged arms 95
C, carrying seed-boxes at their rear ends, the
diametrically-operated slides in engagement
with said seed-boxes operated by the toothed
cam-wheels, the boot or runners *D*, connected
100 to the arm *C* by curved link, and the rods or
levers connected to said boots or runners and
extending to the forward part of the machine,
whereby the said arms and boots or runners
may be raised, as set forth, substantially as
described.

In testimony whereof we affix our signatures
in presence of two witnesses.
